UNITED STATES PATENT OFFICE.

FRED THOMPSON, OF BOSTON, MASSACHUSETTS.

DRAW-STRING BAG.

No. 916,802.

Specification of Letters Patent. Patented March 30, 1909.

Application filed July 13, 1907. Serial No. 383,634.

To all whom it may concern:

Be it known that I, FRED THOMPSON, a citizen of the United States, residing at Boston, in the county of Suffolk and State of Massachusetts, have invented certain new and useful Improvements in Draw - string Bags, of which the following is a specification, reference being had therein to the accompanying drawing.

10 My invention consists of improvements in draw-string or purse-string bags, and especially such as are used as containers for tobacco.

It is designed first, to facilitate the opening 15 and the closing of the bag; second, to do away with the inconvenient knot with which such bags are secured when placed on the market; and third, to provide means whereby the bag may readily be securely closed, 20 and opened.

Figure 1 represents a perspective view of the usual form of draw-string tobacco bag when filled, closed, and supplied with my invention. Fig. 2 is an enlarged detail 25 showing a pair of draw-strings, an opening member, and a portion of the mouth of the bag. Fig. 3 shows, in full lines, how the bag may be opened; the dotted draw-strings and fingers illustrate how by moving the fingers 30 into the dotted positions and drawing upon the strings, the mouth of the bag may be closed. Fig. 4 shows the bag securely closed. Fig. 5 represents a modification.

In the drawings illustrating the principle 35 of my invention, and the best method of embodying that principle, now known to me, are shown a draw-string bag A provided with a pair of draw-strings B, B', and a pair of wire spiral opening members 1, 1', which 40 by means of hooks 2, 2', that obviously may be closed to prevent the hooks from being detached from the bag, are secured to the edge portion a, Fig. 2, forming the mouth of the bag. The draw-string, as B, instead of 45 being drawn directly through the passage b, formed in the edge portion, a, of the bag, as is usually the case, is first drawn through its respective opening member 1, then through one part of said passage, through a hook 2', 50 Fig. 3, of the other opening member 1', through the other part of said passage b in the opposite edge portion of the bag, and then through and out of the free end of its respective opening member 1. The other 55 draw-string as B', is drawn through its opening member 1', the passageway b, the hook

2, Fig. 2, of the opposite opening member 1, the rest of the passage, and then through and out of its respective opening member 1'. The free end portions of each draw-string 60 are then tied together; the mouth of the bag is closed; and each draw-string secured to a side of the bag, as by being pasted or stuck thereto by a paper wrapper C, Fig. 1, or other suitable means; the free ends of the 65 draw-strings, after being thus secured, being left free under the lower edge of the wrapper C, so that each string may be readily grasped, and used to tear through the paper wrapper, and thus, when released, to permit the opening 70 of the bag.

Users of the purse-string or draw-string tobacco bags are often inconvenienced in their efforts to untie the usual draw-string bowknot which, for example, during the act 75 of untying, or the act of removing the revenue stamp pasted over the knot and mouth of the bag, frequently becomes a hard knot. Now with my invention, this bowknot is done away with; in fact there is no knot, and 80 no likelihood of an accidental knot. The exposed portions of the strings B, B', instead of being tied in a knot over the mouth of the bag, and stuck down by a revenue stamp, are straight, distant from the mouth, and out of 85 contact with the stamp, so that there is no possibility that the strings may become accidentally tangled or tied, and the user inconvenienced; all of which is made doubly 90 obvious by another inspection of Figs. 1, 3 and 4. After the draw-strings have become freed, it is often difficult and exasperating to open the mouth of the bag, if the bag is not provided with my invention; the fingers of both hands being required to pick it open. 95 Further, when opening such a bag, the user often would like, were it possible, to have one hand free to manipulate a pipe or a cigarette paper, but cannot because both hands are occupied in digging at the closed mouth 100 of the bag. Now this annoyance can be avoided by the use of my invention. To open the bag, the coils 1, 1', Fig. 3 may be grasped, between the thumb and forefinger of each hand, and be separated in the way 105 shown in full lines, and the mouth of the bag opened to the desired extent; the draw-strings gliding freely through the coils, without contacting the fingers. If one desires, 110 he may use his teeth instead of one hand in the above mentioned operation.

It is to be remembered that each draw-

string passes through the hook of the opposite coil, so that in opening the bag, should there be tension upon one opening member or coil and one draw-string, the tension would 5 be borne by the hook, and not by the hook and the edge of the bag, as would be the case did the draw-string not pass through the hook; there would, therefore, be no tendency to tear that part of the bag which otherwise 10 would be subjected to the tension due to the draw-string and the coil.

To close the bag, seize the coils B, B, Fig. 3, allow the fingers to slip off the free ends of the coils and on to the draw-strings, and then 15 draw the draw-strings in opposite directions, in the manner shown in dotted lines. As in opening the bag, so in closing, the teeth may be used instead of one of the hands.

To have one hand free during either the 20 opening or the closing of the bag, is a great convenience to cigarette smokers. Further, these opening members quickly guide the fingers to the strings.

Users of purse-string tobacco bags seldom 25 re-tie the knot to secure the contents of the bag, because to do so is too much trouble. With my invention, if additional security is desired, this trouble is reduced to a minimum, as will now appear. After closing the 30 bag, first grasp the ends of both draw-strings between the thumb and forefinger of the right hand and suspend the bag. This causes the purse-strings and coils to become parallel. Second, with the left hand, grasp 35 the top of the coils, and the strings as they emerge from same, and after drawing the strings tightly through the coils, take several turns around both coils with one or both strings in the right hand; the strings lying 40 between the spiral turns of the coils, as in Fig. 4. The coils thus become bound together, and at the same time, the contained purse or draw-strings become fixed, and are prevented from loosening. Obviously, the 45 bag may be quickly, easily, and securely closed, and opened.

In Fig. 5, I have shown a modified form of opening members. Instead of being in the

form of a wire spiral, a simple and cheap form of construction, they are made of small 50 tubes.

Having described the construction and operation of my invention and desiring to protect it in the broadest manner legally possible, what I claim is:—

1. A bag having a pair of draw-strings; a pair of wire spiral opening members secured to the edge portions of the bag; said draw-strings leading through said members.

2. A bag having a pair of draw-strings; a pair of opening members each provided with a hook; one draw-string being led through one opening member and the hook of the second member; while the other string is led through the second member and the hook 65 of the first member.

3. A bag having a pair of draw-strings; a pair of opening members each provided with a hook to secure said member to the edge portion of the bag, forming the mouth 70 of the bag; one draw-string being led through one opening member and the hook of the second member, while the other string is led through the second member and the hook of the first member.

4. A bag having a pair of draw-strings; a pair of wire spirals each provided with a hook; one draw-string being led through one spiral and the hook of the second spiral, while the other draw-string is led through 80 the second spiral, and the hook of the first spiral.

5. A bag having a pair of draw-strings; a pair of wire spirals, each provided with a hook to secure said wire spiral to the edge 85 portion of the bag, forming the mouth of the bag; one draw-string being led through one spiral, and the hook of the second spiral, while the other draw-string is led through the second spiral, and the hook of the first spiral. 90

In testimony whereof I affix my signature in presence of two witnesses.

FRED THOMPSON.
